J. F. O'CONNOR

REFRIGERATOR CAR DOOR OPERATING MECHANISM

Filed Oct. 23, 1925

Fig.1

Patented Sept. 25, 1928.

UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

REFRIGERATOR-CAR-DOOR-OPERATING MECHANISM.

Application filed October 28, 1925. Serial No. 64,294.

This invention relates to improvements in refrigerator car door operating mechanism.

An object of the invention is to provide a door operating device and fastener for a pair of pivoted refrigerator car doors, in which one of the doors is provided with fastening means for securing it in closed position, and which door is provided with lever means swingably mounted thereon near the forward edge thereof, said lever means being provided with spaced engaging portions adapted to co-act with the inner and outer faces of an abutment member secured adjacent the forward edge of the other door, whereby swinging movement of the lever means effects opening and closing movements of the door upon which the abutment member is mounted.

Other and further objects of the invention will more clearly appear from the description and claims hereinafter following.

In the drawings, Figure 1 is a fragmentary broken view of a refrigerator car, showing the side doors in front elevation, with the door fastening and operating means applied thereto; Figure 2 is a sectional view of the invention on the line 2-2 of Figure 1, showing certain parts of the mechanism in elevation; And Figure 3 is a fragmentary sectional view of the car door showing the locking lever in side elevation.

Referring to the drawings, 5 and 6 designate hinged refrigerator car doors, the door 6 being the last one to be closed, said doors being provided with beveled meeting edges as indicated at 7 in the usual manner, and suitable packings are provided on said meeting edges and also around the outer edges of the doors and door frame. As is customary, the door 5, which is the first door closed, is provided with a wear plate 8 at its bottom forward corner, said plate being adapted to be engaged by the pivoted latch 9 when the door is closed.

The improved door operating mechanism comprises an abutment member A; operating lever B; and locking means C by which the operating lever is secured in position.

The abutment member A is in the form of an elongated metallic plate, having a central web portion 10, upon the longitudinal edges of which are formed out-turned flanges 11 extending throughout the length of the abutment member, said abutment member at its rear end being provided with wings 12.

The abutment member is secured to the door 6 in a position substantially intermediate the top and bottom edges of the door, by means of bolts 13-13, one of which extends through each wing 12 and the others of which extend through the web portion 10. The forward portion of the plate extends outwardly beyond the edge of the door 6 a suitable distance to provide a projection 14, which is curved so as to off-set the inner engaging face 15 of the projection outwardly relative to the plane of the faces of the doors when closed. The outer face 16 of the curved portion 14 provides a cam surface adapted for cooperation with the lever means B, as hereinafter referred to, the inner and outer faces of said projection being bounded adjacent their side edges by the flanges 11 which provide a pocket-like recess on the inner face of the curved projection 14, and a channel on the outer face.

The lever means B are secured to the door 5 horizontally in line with the abutment member A. Said lever means comprise a mounting bracket 17 substantially rectangular in form, each corner of the bracket having a bolt 18 extending therethrough by means of which the bracket is secured to the door 5. The bracket 17 is provided with up-standing ears 19-19 adapted for the reception of a pivot pin 20, and between said ears, and extending somewhat toward the forward edge of the door 5, the bracket is cut out as indicated at 21, for a purpose which will be hereinafter described. Mounted upon the pivot pin 20 are the lever means proper, which include a handle portion 22, and a reversely extending offset actuating portion 23. The handle portion adjacent the pivot pin 20, is outwardly curved as indicated at 24, to provide what is in effect an inner cam surface adapted to co-operate with the outer face 16 of the abutment member. Formed integrally with the handle, is the actuating portion 23, said portion being disposed on the side of the pivot pin 20 opposite to the bearing portion 24 of the handle member and extending substantially parallel therewith, said actuating portion working in the cutout part of the bracket 17 and forming with the bearing portion 24 a recess 25 which is adapted to snugly accommodate the nose 26 of the abutment member A when the doors are in closed position. The handle portion 22 of the lever means B is of such width that it fits nicely between the flanges 11 on the abutment member when the doors are in closed

position and the handle locked to the door 6 by the locking means C.

The locking means C include a mounting lug 27 formed on the upper wing 12 of the 5 abutment member, said lug being perforated for the reception of a pivot pin 28 upon which are mounted the forked ends of the lever 29, said lever being hung on the pivot pin so that it may depend across the outer end of the handle 22, and the lever 29 at the lower side of the abutment member A is provided with an aperture 30 for the reception of a keeper 31 formed integrally with the lower wing 12 of the abutment member, said keeper being 15 adapted for the reception of a locking element. A handle 32 is formed on the lever 29 whereby the same may be operated.

In operation, assuming the doors to be closed as illustrated in the drawings, in order 20 to open the right-hand door, the locking element is detached from engagement with the keeper 31 so that the lever 29 may be lifted so as to free the end of the handle 22. Outward swinging of the handle 22 effects outward 25 swinging of the actuating portion 23 of the lever means, which bears upon the curved surface 15 of the curved projection 14, whereby the door 6 is forced outwardly a sufficient distance so that the same may be thereafter 30 swung to fully opened position with little difficulty. The lefthand door may then be opened by releasing the latch 9. In closing the door, the lefthand door is first slammed shut and the latch turned to engaging position. The righthand door is then swung in a 35 closing direction, and the nose of the abutment member disposed between the actuating portion 23 and the curved portion 24 of the lever means B. The door ordinarily cannot be 40 conveniently fully closed because of the resistance offered by the insulation between the door edges, and in order to overcome this resistance and fully close the door, the cam face 24 of the handle member 22 comes into bearing 45 engagement with the outer curved face 16 of the nose of the abutment member A, whereby continued movement of the handle 22 inwardly toward the car gradually forces the door to 50 fully closed position, the handle 22 being then secured by moving the lever 29 over the end of the same, and attaching the locking means.

While I have herein shown and described what I now consider the preferred manner of carrying out my invention, the same is merely 55 illustrative and I contemplate all changes and modifications that come within the scope of the claims appended hereto.

I claim:

1. In a car door fastener, the combination 60 with a pair of doors mounted to swing about

vertical axes and having their free edges adapted to abut in closed position; means for fastening one of said doors when the same is in closed position; of a bracket mounted upon said door adjacent the forward edges thereof, within the top and bottom edges thereof, said bracket being provided with a pair of vertically spaced upstanding ears carrying a pivot pin; of an abutment member mounted adjacent the forward edge of the other door and projecting beyond said forward edge, said abutment member being channel-shaped in form and provided with a curved nose portion at its outer extremity, the inner extremity of said abutment member being widened and having means thereon to pivotally support a locking lever at the upper end, said widened portion at its lower end having an eyelet adapted to engage an opening in said locking member; and a lever fitting within the channel in said abutment member, the end of said lever adjacent said locking member being adapted to be engaged by the latter to lock the same in position, the opposite end of said lever member being pivotally mounted upon the pivot pin on the first mentioned door, said lever being adapted to engage the outer side of the nose of said abutment member and said lever being provided with a reversely turned actuating portion adapted to engage the inner side of the nose of said abutment member, whereby swinging movement of said lever effects movement of said other door in opening and closing directions. 95

2. In a car door fastener, the combination with a pair of car doors mounted to swing about vertical axes and having their free edges adapted to abut in closed position; of an elongated lever having a body portion and an integral reversely extending end portion spaced from said body portion, said lever member being pivotally mounted adjacent the forward edge of one door to swing about a vertical axis located between the main body portion of the lever and the reversely turned portion; and abutment means secured to the forward edge of the other door, said abutment means being provided with a projection adapted to snugly fit between the reversely turned portion and body portion of said lever, whereby movement of said lever effects movement of said doors in opening and closing directions, and maintains said doors in alignment when closed. 110

In witness that I claim the foregoing I have hereunto subscribed my name this 21st day of October, 1925.

JOHN F. O'CONNOR.
